UNITED STATES PATENT OFFICE.

WILLIAM W. DRYDEN, OF PHILADELPHIA, PENNSYLVANIA.

ELECTRIC SWITCH.

1,320,677.

Specification of Letters Patent.

Patented Nov. 4, 1919.

Application filed September 21, 1917. Serial No. 192,489.

To all whom it may concern:

Be it known that I, WILLIAM W. DRYDEN, a citizen of the United States, and a resident of the city of Philadelphia, county of Philadelphia, State of Pennsylvania, have invented certain new and useful Improvements in Electric Switches, of which the following is a specification.

My invention relates to switches for closing and opening an electric circuit and it has for one of its objects to provide a construction of switch in which the switch or contact members have connection with a rectilinear movable member rather than a rotary member.

A further object is to provide a construction in which a spring which effects movement of the movable switch or contact members normally is not under tension but is adapted to be placed under tension and then released to cause movement of a switch or contact actuating part to effect movement of said contact members to close or open an electric circuit.

Another object of my invention is to provide a construction in which, during the operation of turning the switch control key to cause the opening or breaking of the circuit, the contact or switch members are first tightened against their coöperating stationary contact members and are then suddenly released, thereby reducing the amount of sparking between the contact points.

It is also an object of my invention not only to simplify the construction, but also to provide one which is very strong and durable and which is very efficient as compared with such structures heretofore in use as far as I am aware.

Other objects and advantages of my invention will be referred to in the detailed description thereof which follows or will be apparent from such description.

In order that my invention may be more readily understood and its practical advantages fully and clearly appreciated and comprehended reference may be had to the accompanying drawings in which I have illustrated one form of a convenient embodiment of my invention. However, it will be understood that changes in the details of construction may be made without departing from the spirit and scope of my invention.

In the drawings:

Figure 1 is a side elevation of an electric switch embodying my invention, with the

movable switch or contact member out of contact with the stationary contact parts;

Fig. 2 is a top plan view of the switch with the cover shown in Fig. 1 removed; 60

Fig. 3 is a bottom plan view of the switch;

Fig. 4 is a central longitudinal sectional view taken on the line 4—4 of Figs. 2 and 3;

Fig. 5 is a perspective view of certain of the operative parts separated from surrounding parts in order that their construction and arrangement may be more readily seen; 65

Fig. 6 is a perspective view showing the movable switch or contact actuating member 70 surrounding the portions of the structure shown in Fig. 5 and showing the relation of said surrounding part to the parts of said surrounding structure when in position to hold the movable switch or contact members 75 in open position;

Fig. 7 is a central longitudinal sectional view taken on the line 7—7 of Fig. 4, and showing the central operative parts of the structure, the surrounding parts being removed; 80

Fig. 8 is a view showing in separated relation with respect to each other the telescoping members which are shown in assembled relation in other figures of the drawings; 85

Fig. 9 is a view in perspective of the cam for causing relative movement of the telescoping members shown in previous figures of the drawings; 90

Fig. 10 is a view in perspective of the actuator for causing movement of the movable contacts or switches;

Fig. 11 is a view in perspective of a barrel or container in which the parts shown in Fig. 6 are contained and by means of which rotary movement of the switch or contact actuator and the cam is effected; 95

Fig. 12 is a view in perspective of one of the movable contact members or switches; 100

Fig. 13 is a view in perspective of an insulating sleeve or covering employed for surrounding the rods connecting the movable switches or contact members with a plate having connection with the actuator 105 aforesaid;

Fig. 14 is a transverse sectional view taken on the line 14—14 of Fig. 4, the parts surrounding the portion of the structure shown in said Fig. 14 being removed or omitted; 110

Fig. 15 is a diagrammatic view of the actuating members of the switch as they

would appear when developed in a plane and illustrating their relative positions when the switch is open; and

Fig. 16 is a similar view showing the relation of these parts when the switch is closed.

Referring to the drawings, 1 designates a switch casing of insulating material such as fiber, porcelain or other suitable material. In and upon this casing the operative parts 10 of the structure are secured.

2 designates a rotatable barrel-like member open at one end and closed at the other, as shown in Figs. 4 and 11. 3 designates a headed screw threaded bolt fixedly secured to the closed end of the said barrel. Said bolt projects through a bushed opening at 4 in the top or closed end of the casing 1. 5 designates a finger key or button having connection with the screw threaded bolt 3 20 by means of which the barrel-like member 2 may be rotated to turn the switch on and off.

It will be noted that the screw threaded member 3 also extends through the top 8 25 of a cover having sides 9. The portion of said cover outside of the reduced projecting end portion 10 of the casing is provided with an inner lining or sheet of insulating material 11.

30 12 and 13 designate movable switch or contact members, the opposite ends of which are adapted to contact with stationary contact members 14, 15, 16 and 17 secured to the shoulder portion of the casing 1 sur- 35 rounding the reduced projecting end portion 10. 18, 19, 20 and 21 designate binding posts and screws by means of which the wires of the circuit are connected to the switch so that the current may be passed 40 through the said switch. The members of the respective couples of binding posts, 18 and 20, and 19 and 21, are insulated from each other by the angularly related partition-like portions 22 and 23. The presence 45 of these insulating dividing portions prevents short circuiting between the lines of the circuit within the switch.

24 designates screws by means of which the switch is secured to a wall or other sup- 50 porting structure.

25 designates bolts which are connected respectively to the movable switch or contact members 12 and 13. These bolts, together with covering sleeves 26 therefor, extend through openings 27 through that portion of the top of the switch casing which surrounds the portion 10 and which constitutes the shoulder previously referred to. The said bolts are insulated from the said 55 contact members 12 and 13 by the sleeves 26 and washers 27. The inner or lower ends of the bolts 25 extend through openings formed in projections 28 extending out from the edge of an annular member 29, said 60 projections being in oppositely disposed re-

lation with respect to each other, as shown in Fig. 3 of the drawings. The bolts 25 are secured to these projections by means of nuts and washers 30 connected to their lower ends. 31 designates a flat annular member which is rotatably connected with the flat annular member 29, the latter being recessed to seat the said annular member 31. The said member 31 is held from displacement with respect to the member 29 by means 75 of the headed screws 34.

As shown in the drawings, the annulus 31 is provided with oppositely disposed projecting portions 35 which are rigidly and fixedly secured thereto. These portions are curvilinear in transverse section as shown and are adapted to fit inside of and with their outer surfaces in contact with or in adjacent relation to the inside surface of the barrel 2. These projecting portions 35 are respectively provided at one edge with inclined cam-like portions 36, which portions, however, are not essential to the entirely satisfactory operation of a switch embodying my invention, 90 but such cam portions can do no harm and may, under certain circumstances to be hereinafter referred to, serve a useful purpose. These projecting portions 35 are also provided with oppositely disposed slots 37 as 95 shown in the drawings. The structure comprising the parts 31 and 35 may as a whole be designated as a switch or contact actuator.

39 designates a cam member situated within and surrounded by the said actuator. 100 Said member 39 is provided at its opposite ends with cam surfaces 40 and 41 and is also provided with oppositely disposed screw threaded openings 42 with which the inner end of short screws 43 are engaged. The 105 said screws extend through the barrel member 2 and the curvilinear projecting portions 35, as is clearly shown in Fig. 14, the heads thereof being situated within the openings 45 in the barrel member 2 and within the 110 slots 37 of the projections 35.

By turning the finger key or button 5 the barrel member 2 is rotated, such rotation, by reason of the connection between the said barrel and the parts 35 and 39 through the 115 agency of the screws 43 causes corresponding rotation of the parts 35, 31 and 39. The parts 35 and 31 are rigidly connected together and, as stated, constitute an actuator for actuating the movable switch or contact members.

50 and 51 respectively designate couples of parallel bars, the bars of each couple being arranged in parallel relation to each other. Bars 50 are provided with a head 125 portion 52 in the form of a flat circular disk, which is provided with oppositely disposed slots or notches 53. The bars 51 are likewise provided with a head 54 consisting of a flat circular disk having oppositely 130

disposed slots or notches 55 therein. The slots 53 are arranged in a plane at right angles to the plane of the bars 50. The slots or notches 55 are arranged in a plane at right angles to the plane of the bars 51. When the bars 50 with the head 52 and the bars 51 with the head 54 are placed in engagement and in operative relation to each other the bars 50 project and fit into the 10 slots or notches 55 while the bars 51 project and fit into the slots or notches 53, as is clearly shown in Fig. 5 of the drawings. The bars 50 are provided with laterally and outwardly extending projections 58, one 15 corner of each of which is rounded off as indicated at 59. The bars 51 are also provided with projections 60, one corner of each of which is rounded off as indicated at 61. These rounded off corners 59 and 61 are 20 adapted to contact with the cam surfaces 41 and 40.

The head or disk 54 is provided with a projection 65 having a squared end, as indicated at 66, which is adapted to engage a 25 correspondingly shaped opening in a cross-bar 67, the opposite ends of which are seated in notches 68 in oppositely disposed relation to each other in the switch casing 1. The purpose of providing this cross-bar and 30 fastening it non-rotatably to the projection 65 and positioning its opposite ends in the notches 68 is to prevent rotation of the frame structure consisting of the bars 50, 51 and the respective disks 52 and 54 when 35 the barrel 2, the switch or contact actuator 31-35, and the cam member 39 are rotated.

The cam member 39 is situated between the projections 58 and 60, as is clearly 40 shown in Fig. 5 of the drawings. Normally the couples consisting of the bars 50 and 51 with the heads thereof are in extended 45 relation with respect to each other as shown in the drawings, being moved into that position after each operation of the key 5 to open and close the switch by means of the coiled spring 70, said spring being situated 50 between the four bars 50 and 51 as shown. Normally the said spring is not under tension or at least the tension is very slight. 55 Owing to the fact that the spring 70 normally is not under tension its life or length of service is greatly increased.

For the purpose of indicating when the switch is open or closed I have provided a 55, slidably supported plate 71 which is situated within the side 9 of the cover, said plate fitting over an opening 72 in the said cover. The words "On" and "Off" are placed upon the outer side or surface of the 60 plate 71. The inner side of the said plate is provided with inwardly extended projections 73 between which the movable contact member 12 is situated, so that movement of the latter causes movement of the plate 71 into 65 to carry the words "Off" and "On" into

position in registry with the rectangular opening 72, as is clearly apparent from Fig. 1 of the drawings.

In operating the switch the finger key 5 is turned toward the right and as heretofore 70 stated rotation of the said finger key causes rotation of the barrel 2 and rotation of the latter causes rotation of the movable contact actuator 31-35 and the actuating cam member 39. 75

The operation of the device may perhaps be best understood by reference to Fig. 15 of the drawings. From the previous description it will be remembered that the member 39 is directly connected to the barrel 2 by the screws 43 and that the said members 39 and 2 are relatively immovable. In consequence the member 39 is capable only of rotary motion. The member 39 comprising the cam portions heretofore 80 mentioned may thus be considered as a cam actuating member. As is apparent from the drawings, particularly Fig. 15, when the cam actuating member 39 is moved to the right the cam edges 40-40 will simultaneously 85 engage the lugs 60-60 and by reason of the coöperation between the said lugs and the said cams the disk 54 will be raised, compressing the spring 70. In this manner the necessary energy is stored up in the 90 spring for causing the subsequent instantaneous snapping action of the switch. Directly after the lugs 60 have been moved along the cams 40 to the maximum extent they are quickly or suddenly released and 95 engage the upper horizontal edges of the projections 35, which under the action of the spring 70, will be shifted to the position illustrated in Fig. 16. As already described, the movable switch members 12 and 13 are 100 indirectly attached to the annulus 31 which is directly united with the projecting parts 35-35 and as a result the said switch members 12 and 13 will be shifted to close the 105 switch. If further movement of the cam member 39 to the right be considered in connection with Fig. 16 it will be noted that the cams 41-41 will engage lugs or projections 58-58, and as the said lugs ride up on to the said cams 41-41 movement of the 110 disk 52 will be caused to compress the spring 70. As the lugs or projections 58 pass from the highest portions of the cams 41 they engage beneath the parts 35-35 and 115 raise the same quickly to open the switch, the movable parts of the switch thereby again assuming the position shown in Fig. 15 of the drawings. Further rotation of the parts by means of the finger key 5 causes a repetition of the operation as previously 120 described in connection with Fig. 15 and so on alternately.

It will now be apparent why, when the key 5 is turned to open the circuit, the first effect is to tighten the movable switch or con- 125

tact members against the stationary contact members. In Fig. 16 the parts are shown with the circuit closed. As the parts 31-35 and 39 are moved toward the right movement of the bars 50 and the disk 52 downwardly, having reference to Fig. 16, is effected, compressing the spring 70 against the disk 54. The bars 51 being connected to the latter and the lugs or projections 60 of said bars resting upon the edges of the parts 35, as shown in Fig. 16, and the movable switch or contact members having indirect connection with the actuating member 31-35, as previously described, it is apparent that the pressure of the said spring which is transmitted through the disk 54, the bars 51 and the lugs or projections 60 to the parts 35 and in turn transmitted by the said parts to the movable contact or switch members operates to press the same tightly against the stationary contact members of the switch. The tension of the spring and the resultant pressure of the movable contact members increases until the lugs or projections 58 pass beyond or escape from the cams 41. The said projections then engage the right hand ends of the lower edges of the parts 35 (see Fig. 16) while at the same time the lugs or projections 60 are disengaged from the upper edges of said parts with the result that the expansive action of the spring snaps the said parts 35 upwardly causing a quick or sudden opening movement of the movable contact or switch members 12 and 13.

It will be observed that the outer ends of the lugs or projections 58 and 60 extend over the inclined surfaces 36 upon the parts 35. The presence of these inclined surfaces renders it unnecessary that the high parts of the cams 40 and 41 shall terminate in exact alinement with the beginning of the top and bottom edges of the parts 35. If these inclined surfaces 36 were not present and if the high points of the cams 40 and 41 should terminate below the upper or lower edges of the parts 35 it might be that the projections 58 or 60 would strike against the side edges of these parts and thus prevent the further rotation of the rotatable parts previously described, thereby preventing proper operation of the switch.

I claim:-

1. In an electric switch, the combination of telescoping members, a yielding device intermediate said members tending to hold them in separated relation with respect to each other, rotatable means for alternately moving said members in opposite directions to compress said yielding device, movable contact members and means actuated by the alternate movements of said telescoping members to cause movement of said movable contact members to open and close an electric circuit.

2. In an electric switch, the combination of telescoping members, an elastic member interposed between said members and tending to hold them in separated relation with respect to each other, said members each having laterally extending projections, the said projections being arranged in planes substantially at right angles to each other and extending longitudinally of the switch, a member interposed between the said projections and adapted to contact therewith to cause relative movement of the said telescoping members, movable contact members and an actuator for said contact members, said actuator being actuated in opposite directions alternately by the said telescoping members.

3. In an electric switch, the combination of telescoping members, an elastic device intermediate said members and tending to hold the same in separated relation with respect to each other, said members each being provided with a couple of lugs or projections situated in oppositely disposed relation to each other and extending outwardly therefrom, the lugs or projections upon one of the said members being situated in a plane substantially at right angles to the plane in which the other lugs or projections are situated, a rotatable cam actuating member situated intermediate the respective couples of projections and surrounding the said telescoping members, the said cam actuating member contacting with the said projections to cause relative movements of the said telescoping members, movable contact members, an actuator for the said contact members, the said projections upon the respective members of the said telescoping members being adapted to contact at oppositely disposed points of the said actuator when released from said cam actuating member to cause movements thereof in alternate directions to thereby cause movements of the said movable contact members to open and close the same.

4. In an electric switch, the combination of telescoping members, each member comprising opposite leg portions and said leg portions provided with laterally extending projections or lugs, a spring interposed between the said telescoping members and tending to hold the same in separated relation with respect to each other, a rotatable tubular member surrounding the said members and situated between the said projections, the said tubular member having cams upon its opposite ends, the cams on each end being arranged in oppositely disposed relation to each other and being adapted to simultaneously contact with each of the projections upon one of the telescoping members to cause movement of such member to compress the said spring and to simultaneously become disengaged therefrom to per-

mit movement of the said telescoping members under the influence of said spring, movable contact members, an actuator therefor, the said actuator comprising parts situated 5 against or near the said rotatable tubular member, its opposite ends being adapted to be alternately contacted with by the said projections as they are released from the cams upon the said tubular member to cause 10 movement thereof in opposite directions to thereby cause opening and closing movements of the said contact members.

5. In an electric switch, the combination of telescoping members, each of the said 15 members comprising a couple of oppositely disposed bars, said bars being provided with laterally extending projections or lugs, means for preventing rotation of said members, said members being movable, however, 20 longitudinally, a tubular rotatable member embracing the said telescoping members and situated intermediate the two couples of projections, said tubular member being provided with a couple of oppositely disposed 25 cams upon each of its ends, said cams being adapted to contact with the said projections to cause relative movement of the said telescoping members toward each other, movable contact members, an actuator having connection 30 with the said contact members, said actuator comprising parts situated against or near the said rotatable tubular member, the projections constituting one of the said couples contacting with the ends of said 35 parts upon one side of the said actuator during the time that the projections constituting the other couple are riding up upon the cams of the said rotatable member with which they co-act and the said first mentioned projections being disengaged from the said parts as the second named projections leave the said cams and pass on to the opposite ends of the said parts, and means for causing relative movement of said 40 telescoping members away from each other upon disengagement of said cams from said projections, substantially as described.

6. In an electric switch, the combination of a casing, a barrel member situated therein, means for causing rotation thereof, a rotatable tubular cam actuating member situated in said barrel, means for rigidly connecting the said cam actuating member with the said barrel, movable contact members, an 55 actuator for causing movement of the said contact members, said actuator being provided with parts having slidable connection with the said second named means, telescoping members extending through the said 60 rotatable tubular cam actuating member, said telescoping members respectively being provided with couples of lugs or projections, the projections constituting one couple and those constituting the other being situated 65 upon opposite sides of the said tubular cam

actuating member and being adapted to be actuated thereby as the same is rotated and said projections being adapted to contact alternately with opposite ends of said actuator, the said projections of the respective 70 couples being adapted to be alternately acted upon by and released from the cams of said cam actuating member, and means for causing relative movement of said telescoping members upon release of said projections 75 from said cams, whereby alternate movements in opposite directions of the actuator for actuating the said contact members are effected.

7. In an electric switch, the combination 80 of telescoping members, the said members each comprising oppositely disposed bars, said bars each being provided with outwardly extending projections or lugs, the said bars and projections being arranged in 85 planes substantially at right angles to each other, a coiled spring interposed between the said telescoping members, said spring tending to hold the said members in separated relation with respect to each other 90 and being normally uncompressed or un tensioned, a rotatable tubular cam member embracing the central portions of said telescoping members intermediate the said projections, said tubular member having oppositely disposed cams upon its opposite 95 ends, said cams being adapted to alternately engage and disengage the said projections to cause relative movement of said telescoping members to compress and release said 100 spring, a barrel-like member in which the said telescoping members and the said rotatable tubular member are situated, means for connecting the said barrel-like member with the said tubular member, means for rotating 105 the said barrel-like member and thereby causing rotation of the said rotatable tubular member, movable contact members, and an actuator having connection with the said contact members for causing movement of 110 the latter, said actuator including parts situated intermediate the said rotatable tubular member and the said barrel member and having slots through which the means for connecting the said barrel and the said 115 rotatable tubular member extend whereby the said actuator may have both a rotary and a reciprocatory movement, the latter movement being caused by contact of the said projections alternately with opposite 120 ends of the said parts.

8. In an electric switch, the combination 125 of switch or contact members, contacts for co-acting with said members, an actuator, connections between said actuator and said members, means for causing movement of said actuator alternately in opposite directions to move said contact members into and out of contact with said contacts, and means whereby previous to a movement of said 130

contact members out of contact with said contacts the pressure of the said members against the said contacts is increased, such increase of pressure continuing until the 5 moment of separation of said contact members and contacts.

9. In an electric switch, the combination of switch or contact members, contacts for co-acting with said members, an actuator, 10 connections between said actuator and said members, telescoping members, said members having projections, those on one of the said telescoping members adapted to engage one end of the said actuator and those on the 15 other of said telescoping members adapted to engage the opposing end of said actuator, a spring situated within the said telescoping members, and a tubular cam actuating member inclosing the central portion of the 20 said telescoping members and being situated intermediate the said projections and having cam surfaces upon its opposite ends which are adapted to contact with the said projections and cause relative movement of 25 the said telescoping members toward each other at intervals, when the said cam actuating member is rotated to compress the said spring, compression of said spring, when the contact members are in contact with their 30 contacts, increasing the pressure of the said contact members against the said contacts, and the expansion of said spring, when the said projections are released from the said cam surfaces, causing movement of the said 35 actuator to effect opening or closing movement of the said contact members, substantially as described.

10. In an electric switch, the combination

of switch or contact members, contacts for co-acting with said members, an actuator, 40 connections between said actuator and said members, means for causing movement of said actuator alternately in opposite directions to move said contact members into and out of contact with said contacts, a 45 spring for causing movement of said actuator, said spring extending transversely of and substantially at right angles to the plane of the said contact members, and means for compressing the said spring and for causing 50 the pressure thereof to be exerted upon the said contact members until the latter suddenly move away from the said contacts.

11. In an electric switch, the combination of switch or contact members, contacts for 55 co-acting with said members, an actuator, connections between said actuator and said members, means for causing movement of said actuator alternately in opposite directions to move said contact members into and 60 out of contact with said contacts, a coiled spring extending transversely of and substantially at right angles to the plane of said contact members, a housing for said spring, said housing comprising relatively movable 65 members, means for causing alternate movement of the said housing members for compressing the said spring, and means for releasing the said housing members to permit sudden expansion of said spring to effect 70 movement of the said contact members.

In testimony that I claim the foregoing as my invention, I have hereunto signed my name this 20th day of September, A. D. 1917.

WILLIAM W. DRYDEN.
